RAZOR BLADE AND HOLDER

John Holtzman, New York, N. Y.

Application February 21, 1931, Serial No. 517,497

13 Claims. (Cl. 30—12)

This invention relates to safety razors and to the blades to be used in such razors. My invention contemplates, among other things, the provision of simple and efficient means for properly and accurately positioning a blade in the holder therefor, as when the holder is assembled ready for shaving, which means allows the easy removal of the blade from the holder, when desired.

10 Fig. 1 is a side elevation of a form of my improved razor adapted for use in connection with rigid blades, and having a swinging clamping member.

15 Fig. 2 is a rear elevation of the upper part of the same.

Fig. 3 is a vertical section of the same, taken on the line 10—10 of Fig. 2, and showing the parts in blade releasing position.

20 Fig. 4 is a top plan view of the same, showing part of the blade positioning and clamping member broken away to show the underlying structure, and showing part of the blade.

Fig. 5 is a perspective view of the guard member and handle.

25 Fig. 6 is a perspective view of one form of rigid blade adapted to be used in the holder.

Fig. 7 is a similar view of another form of a rigid blade.

Referring now to Figs. 1 to 3 inclusive, I have 30 there shown a modified form of my improved razor wherein the blade may merely be laid on the guard member, the blade being automatically moved into shaving position by the clamping member on the operation of the handle. In 35 this form of my improved razor, the guard member 150 terminates in the guard teeth 151 and is preferably though not necessarily made integral with the upper portion 152 of the supporting shaft therefor. Said portion 152 is inserted into 40 a suitable recess 153 in the hollow handle 154 and is normally urged upwardly and out of the handle by means of the compression spring 155 inserted into the recess 153 and surrounding the extension 156 of the guard supporting member. 45 Said extension 156 passes through the handle 154 and is threaded at its lowermost end as at 157 for engagement with the rotatable nut 158.

A suitable guide slot as 159 is made in the member 156, said slot being engaged by the pin 50 160 to prevent rotation of the member 156 relatively to the handle 154. It will be seen that on rotation of the nut 158 in the proper direction, the spring 155 moves the support 156 and the guard 150 carried thereby upwardly relatively to the handle. The guard member 150 is

provided with a suitable upstanding projection 161 designed to pass through the slot 162 of the blade 163 and to position said blade longitudinally of the guard. Said projection 161 is, however, of less width than the slot 162 so that the blade may move transversely of the projection without said projection leaving the slot, as will be more fully described hereinafter. The clamping member 165 is provided with a top and with depending sides 166 adapted to fit over the ends 5 of the guard member. Depending from the back 167 of the clamping member are a pair of spaced arms 168 curved at their lower ends 169 and pivoted at their extremities 170 to the member 152 by the insertion of said extremities into suitable hollows in said member 152. The curved portions 169 act as cams cooperating with the bifurcated members 171 secured to the upper end of the handle 154 for that purpose.

It will be seen that after the blade 163 has 20 been inserted on the upper surface of the guard member 150 and the parts are in a position indicated in Fig. 3, rotation of the nut 158 in a clockwise direction, as viewed in Fig. 3, moves the handle 154 relatively to the member 156 or 25 moves said member downwardly relatively to the handle 154 whereby the extremities 170 about which the clamping member is pivoted, is drawn downwardly relatively to the members 171 which thereby serve as pivots to swing the clamping 30 member toward closed position while they slide along the surface of the curved portions 169. At this time, the bevelled or inclined portion 172 of the top of the clamping member engages the rear edge 173 of the blade and pushes said blade forwardly, the projection 161 thereby moving in the slot 162, and the blade moving forwardly until its edge 173' engages the upstanding stops 174 at the ends of the front edge of the guard member.

40 To remove the blade, the nut 158 is turned in the opposite direction whereby the spring 155 moves the clamping member upwardly relatively to the handle and the members 171 by their engagement with the curved portions 169 swing the 45 clamping member in a clock-wise direction about the extremities 170 as a pivot.

In the modified form of my improved razor shown in Figs. 4 and 5, the guard member 175 is provided with positioning projections 176 50 adapted to engage edge recesses 177 in the blade 178. It will be understood that the width of said recesses 177 is slightly greater than the corresponding width of the projections 176 so that the blade may move transversely into shaving 55

position as the clamping member is moved into place.

It will be understood that while I have shown various specific embodiments of my invention, I do not desire to limit myself thereto but intend to claim my invention as broadly as may be permitted by the state of the prior art and the scope of the appended claims.

I claim:

10. 1. In a safety razor, a blade-supporting guard member, a clamping member serving as a cover for the blade and for the guard member, and engaging and moving the blade transversely of the guard member on the movement thereof into blade clamping position, a reciprocating extension depending from the guard member, an arm depending from the clamping member and pivoted to the extension, a spring urging the extension and the guard member as a unit in a direction to open the cover, and means for operatively connecting the clamping member to said extension to swing the clamping member about its pivot on the movement of the extension. 15
15. 2. A safety razor comprising a blade-supporting guard member, a clamping member for clamping the blade on the guard member, an extension depending from the guard member, a hollow handle for the reception of the extension, said clamping member being pivotally connected to the extension, a spring in the handle urging the extension and the guard member out of the handle, and means carried by the extension for moving the extension relatively to the handle to swing the clamping member on its pivot and thereby to clamp and to release the blade. 20
20. 3. In a safety razor, a hollow handle, a spring within the handle, a guard member, a slotted extension on the guard member inserted into the handle and normally compressing said spring, a pin projecting from the handle into the slot of the extension to permit longitudinal movement of the extension in the handle but to prevent relative rotation of the extension and the handle, said spring normally urging the extension out of the handle, a blade covering and clamping member pivoted to the extension below the guard member and above the handle, and cam portions on the clamping member adapted to cause said clamping member to swing on its pivot to cover the blade on the retraction of the extension into the handle against the action of the spring. 25
25. 4. In a safety razor, a guard member, a blade covering and clamping member comprising a pair of spaced aligned pivot portions at one extremity thereof, a blade covering and aligning portion at the other extremity thereof and intermediate spaced cam portions joining the pivot portions and the blade covering portion, said pivot portions being pivoted to the guard member, and means including a handle adapted to slidably carry the guard member for swinging said clamping member about its pivots on the movement of the guard member and the handle relatively to each other. 30
30. 5. In a safety razor, a blade-supporting guard member adapted for movement in opposite directions, a substantially central rectangular stop integral with said guard member, the ends of said stop being spaced apart a distance greater than a third of the length of said guard member, a pair of smaller stops integral with and arranged at the ends of the guard member, a blade covering and clamping member pivoted at an extremity thereof below the guard member, means including a handle slidably supporting the guard member and means for operatively connecting the handle to the clamping member for swinging said clamping member about its pivot into blade-clamping position on the movement of the guard member relatively to the handle in one direction and for swinging said clamping member into blade-releasing position on the movement of the guard member relatively to the handle in the other direction, and a backed blade on the guard member adapted to have the backed edge thereof engaged and moved by said clamping member into operative position on the guard member. 35
35. 6. In a safety razor, a handle, blade-supporting means supported by the handle for movement longitudinally thereof, blade covering and clamping means, an arm depending from said clamping means and pivoted to the supporting means, and a yoke on the handle and arranged intermediate the ends of the arm and through which said arm is passed to movably confine the arm to the handle whereby movement of the handle relatively to the supporting means swings the clamping means into and out of its operative position. 40
40. 7. A safety razor comprising a handle, blade-supporting means slidably carried by the handle, blade-covering and clamping means, a pivot at the lower extremity of the blade-clamping means entering the supporting means, means for sliding the supporting means relatively to the handle, and looped means on the handle embracing a part of the clamping means intermediate the ends of said clamping means, and thereby maintaining said embraced part at a predetermined distance from the handle to swing the clamping means into and out of clamping position on the operation of said sliding means. 45
45. 8. In a safety razor, a movable blade-engaging member including an elongated cylindrical extension, a clamping member for clamping the blade in place, a hollow handle for the reception of the extension, an arm extending from the clamping member, a pivot pin projecting from said arm and entering the movable member, a curved cam portion on the arm, an actuating member for the cam fixed relatively to the handle and adapted to engage the cam at a point adjacent the pivot pin and spaced therefrom a distance not greater than the diameter of said extension, means to prevent relative rotation of the handle and the extension but permitting relative sliding movement thereof, an externally threaded portion on the extension, and an internally threaded member engaging the threaded portion and having a finger piece portion arranged below the handle and adapted to be manually rotated in one direction relatively to the handle to move the extension out of the handle and thereby to move the pivot longitudinally of the handle and away from the handle whereby the cam portion of the arm engages the cam actuating member and said arm together with the clamping member are rotated to uncover and release the blade, said internally threaded member when rotated in the opposite direction swinging the clamping member to cover and clamp the blade. 50
50. 9. In a safety razor, a blade-engaging member, an elongated cylindrical extension on said member, a clamping member, a hollow elongated handle adapted to slidably receive the extension, a pair of spaced arms projecting laterally from the clamping member, a pivot pin portion pivotally supporting the clamping member and operatively connected to the extension and movable 55
55. 70
70. 75

therewith and extending longitudinally of the clamping member from each of the arms adjacent the outermost extremities thereof, a curved cam portion on each of the arms adjacent the pivot pin portion, means fixed relatively to the handle for engaging the cam portions at a point spaced from the pivot pin portion a distance not greater than the diameter of said extension, an externally threaded portion on the extension, a finger piece having a portion engaging said threaded portion and arranged beyond the handle, and means for maintaining the finger piece against movement longitudinally of the handle whereby when the finger piece is rotated in one direction, the extension is moved out of the handle and said pivot pin portion is moved away from the handle to cause the cam portion to engage the cam engaging means and thereby to swing said arm and the clamping member to uncover and release the blade, said finger piece when rotated in the opposite direction swinging the clamping member to cover and clamp the blade.

10. In a safety razor having a guard, a blade covering and clamping member pivotally mounted relatively to the guard, a pair of similar spaced arms extending laterally from an edge of said clamping member, cam means formed on each of said arms, a handle, a movable member within the handle, means for guiding said movable member for movement in a straight line path, means fixed relatively to the handle to engage the cam means on the movement of the movable member to swing the covering member on its pivot to cover and uncover a blade, and a screw threaded finger piece in threaded engagement with the movable member to move said movable member on the rotation of the finger piece in one direction first to swing the clamping member toward blade-covering position, and then to exert clamping pressure on the blade and to progressively adjust the blade relatively to the guard.

11. A safety razor comprising a blade-positioning member for a slotted blade, a blade-clamping element, an extension member depending from the positioning member, a hollow handle for the reception of the extension member, a pivot for the clamping element engaging one of said members and movable with said one member, threaded means carried by the extension member for sliding the extension within the han-

dle, and means for swinging the clamping element on its pivot on rotation of the threaded means comprising cam means on the clamping element and means fixed relatively to the handle for engaging and controlling the movement of the cam means, said controlling means being arranged adjacent the pivot of the clamping element.

12. In a safety razor, a hollow handle, a threaded member slidable in the handle, means for preventing relative rotation of the member and the handle, a finger-piece having a portion in threaded engagement with the threaded member, means for maintaining the finger-piece in position adjacent the end of the handle, blade-positioning means carried by the threaded member, a blade-clamping member, pivot means movable with the threaded member for pivotally connecting the blade-positioning means and the clamping member, and means for swinging the clamping member on its pivot on the rotation of the finger-piece comprising cam means on said arms and means fixed relatively to the handle and arranged in closely spaced relation to the pivot means for engaging the cam means and controlling the movement thereof.

13. In a safety razor, the combination of a razor blade having cut-out portions at each end thereof, and a longitudinal slot therein, blade-positioning means adapted to enter the slot to initially position the blade, said blade-positioning means having an extension, a hollow handle adapted to slidably receive said extension, a blade-clamping and covering member pivotally mounted relative to the blade-positioning means and provided with arcuate cams, means for guiding said extension to move relatively to the handle in a straight line path, means fixed relatively to the handle for engaging the cams to swing the covering member on movement of the cams, a finger-piece rotatably mounted at the end of the handle, and threaded means carried by the finger-piece to move the cams longitudinally of the handle and to swing the clamping member on the rotation of the finger-piece and thereby to produce combined oscillatory and reciprocatory movement of said blade covering member relatively to the handle to clamp and gradually adjust the blade in the razor.

JOHN HOLTZMAN.
